UNITED STATES PATENT OFFICE.

DANIEL S. TUTHILL, OF NEWBURG, NEW YORK, ASSIGNOR OF ONE-HALF TO
HIRAM B. ODELL, OF SAME PLACE.

WAGON-TRUCK.

SPECIFICATION forming part of Letters Patent No. 430,494, dated June 17, 1890.

Application filed April 7, 1890. Serial No. 346,958. (No model.)

To all whom it may concern:

Be it known that I, DANIEL S. TUTHILL, of Newburg, in the county of Orange, and in the State of New York, have invented certain new and useful Improvements in Wagon-Trucks; and I do hereby declare that the following is a full, clear, and exact description thereof, reference being had to the accompanying drawings, in which—

10 Figure 1 is a perspective view of a wagon provided with my truck. Fig. 2 is a like view of the frame of the truck separated from the axle and springs and from the body of the wagon. Figs. 3 and 4 are perspective views from the upper and lower sides, respectively, of the lower platform. Fig. 5 is a like view of a side bar and the truss-beam at their points of union, and shows the means employed for connecting the same together; and 20 Figs. 6 and 7 are perspective views from the upper and lower sides of the upper platform.

Letters of like name and kind refer to like parts in each of the figures.

The design of my invention is to furnish 25 in a compact form a wagon-truck which shall possess all needed strength to enable it to withstand the strains caused by use upon wagons carrying ice or other heavy material; and to such end my said invention consists in 30 the construction of the upper and lower platforms and in their combinations with each other, substantially as and for the purpose hereinafter specified.

In the carrying of my invention into practice I construct from H-beam iron the side bars or hounds A and A and the center bars B and B of the lower platform, of which bars the last named are arranged in parallel lines, while said side bars have their rear ends near 40 to the rear ends of said bars B and B, and from thence forward diverge, as shown in Figs. 2, 3, and 4. Said bars are connected together near their rear ends by means of a channel-bar C, that has its grooved or channeled side 45 turned downward, and is secured to or upon each of the same by means of rivets or bolts which are passed through their horizontal contiguous portions. At the longitudinal center of said channel-bar a block D is fitted 50 into and secured within the channel c, and at

its lower side is adapted to fit upon and be fastened to a cross-spring. From said spring-block said channel-bar has its ends preferably cut away upon upward and outward curved lines to lessen its weight and to cause 55 it to present a more ornamental appearance.

The front ends of the bars A and B are connected together by means of a truss-beam, which is constructed from a T-bar E, that has its web e placed uppermost and its central portion arched upward, as shown, and a flat bar F of equal length, which is either straight or has a slight downward arch at its center, and is secured upon the lower flat side of said bar E by means of bolts or rivets that 60 pass through the portions in contact at and near the ends of said bars. The space between the arched central portions of the bars E and F is adapted to receive the front ends of the bars B and B, which latter are preferably extended slightly beyond the front sides of the former and are securely attached to the same by bolts or rivets that pass through 65 such portions as are in contact.

The front ends of the bars A and A are 70 preferably mitered into the rear portion of the horizontal part or head of the inverted-T bar E, and rest upon the contiguous portion of the upper face of the bar F, as seen in Fig. 3, when said ends are secured in place by 75 means of bolts or rivets, and, if desired, by means of angle-plates. The upper sides of said bars A and A are flush with the upper edge of the web e, as shown in Figs. 2 and 3. A further security is afforded by means of 80 two flat bars G and G, one of which is placed upon the lower face of each bar A and extends along the same to and beneath said bar F, and is securely fastened to said parts by rivets or bolts. The frame or platform 85 thus constructed has secured upon its upper side a circle-iron H, and at the center of the same between and within the channeled sides of the bars B and B carries a block I, which is adapted to receive the body of a king-bolt 90 to furnish an axial bearing for an upper platform.

The ends of the trussed beam are tapered, as shown, and upon the lower side of the bar F, near each end, are provided ears f and f, 95

which are adapted to receive the front ends of the "fore-and-aft" springs employed. Similar ears e' and e' are formed upon the front portion of the upper side of the bar E for the purpose of enabling whiffletrees or shafts to be attached when desired.

The upper platform is constructed from two **H**-bars K and K and a channel-bar L , which bars are arranged in parallel lines with 10 the channel-bar midway between the **H**-bars, and are secured together by means of a circle-iron M , that is bolted or riveted to the lower side of each. At the points where said circle-iron crosses said bar L a block l is fitted 15 into the channel l' and furnishes a bearing for the fastening screw or rivet employed for connecting said parts. At the longitudinal center of said bar L is secured a block N , which preferably is constructed to fill the 20 channel l' and embraces the outer sides of said bar at such point. Said block is adapted to receive and contain a king-bolt O , of usual form, which is inserted from the upper side of the platform and has its head o contained 25 within a recess l^2 , that is provided in the upper side of said bar L . The flanges upon the inner faces at the front ends of the bars B and B are cut away, as shown, for the purpose of furnishing space for the reception of the 30 rear end of a pole, while upon the lower side of the bar F is secured a loop P , to which the equalizer-bar may be attached. The rear projecting portions of each of the bars K and L being cut away, as shown in Fig. 6, so as to 35 lighten them and render their appearance ornamental, the platform is complete and ready for use in connection with the lower platform, as shown in Fig. 2.

In Fig. 1 the truck-frame is shown in position upon an ice-wagon, the upper platform being attached to the frame or bed of such wagon, and the lower platform being connected with and supported by the front axle by means of the usual longitudinal and trans- 45 verse springs.

Having thus described my invention, what I claim is—

1. As an improvement in wagon-trucks, a frame or lower platform which is constructed 50 from **H**-shaped metal bars that are arranged in a line substantially with the draft and have their ends connected together, substantially as and for the purpose specified.

2. As an improvement in wagon-trucks, a frame or lower platform which has its fore- 55 and-aft bars constructed from **H**-shaped metal bars, and the front ends of such bars connected together by means of a metal truss-beam, substantially as and for the purpose shown.

3. As an improvement in wagon-trucks, a truss-beam which is constructed from a **T**-bar of metal and a flat bar of metal that have 60 their ends secured together, in combination 65 with metal bars which extend fore and aft of the truck, and have their front ends connected

by said truss-beam, substantially as and for the purpose set forth.

4. As an improvement in wagon-trucks, a platform which is composed of **H**-bar metal, 70 fore-and-aft bars, a metal truss-beam that is secured upon and operates to connect the front ends of said bars, and a channel-shaped cross-bar which is attached to and serves to connect the rear ends of the same, substantially 75 as and for the purpose shown and described.

5. The lower platform described, in which are combined **H**-shaped fore-and-aft metal bars, a metal truss-beam at their front ends, a 80 channel-shaped metal cross-bar at their rear ends, and a circle-iron that is placed upon and secured to the upper sides of said fore-and-aft bars, substantially as and for the purpose specified.

6. The lower platform described, in which are combined the **H**-shaped fore-and-aft bars, the truss-beam at their front ends, the channel-shaped cross-bar at their rear ends, the circle-iron, and the king-bolt block, substantially 90 as and for the purpose shown.

7. As an improvement in wagon-trucks, a frame or lower platform, which is constructed from **H**-shaped metal bars, two of which are arranged near the center thereof and parallel 95 with each other, and two arranged outside of the latter and diverging from their rear ends, all of said bars extending in the line of draft and having their front and rear ends, respectively, connected together, substantially 100 as and for the purpose specified.

8. As an improvement in wagon-trucks, in combination, the divergent side bars, the parallel center bars, all being **H**-shaped in cross-section, the two-part beam connecting 105 said bars at their front ends, and a bar connecting them at their rear ends, substantially as and for the purpose shown.

9. As an improvement in wagon-trucks, in combination, the divergent side bars, the parallel center bars, the truss-beam connecting them at their front ends, constructed from a **T**-bar of metal and a flat bar of metal, separated at their centers for the reception of the 115 ends of said center bars, but connected at their ends, and a bar for connecting the rear ends of said first-named bars, substantially as and for the purpose set forth.

10. As an improvement in wagon-trucks, in combination, the side bars, the center bars, 120 separated so as to form a space for the reception of a pole, all of said bars being **H**-shaped in cross-section, and having their front and rear ends, respectively, connected together, and the king-bolt block between said center 125 bars, substantially as and for the purpose described.

11. As an improvement in wagon-trucks, in combination, the **H**-shaped metal bars extending in the line of draft, the bar connecting the rear ends thereof on their under sides, 130 and the beam extending across the front ends

thereof, and having a miter connection therewith, substantially as and for the purpose specified.

12. As an improvement in wagon-trucks, an upper platform, which is composed of two H-shaped bars and a channel-bar, that are secured together in parallel lines by means of a circle-iron, substantially as and for the purpose set forth.

13. The hereinbefore-described upper platform, in which are combined the H-shaped and the channel bars, the circle-iron, and the king-bolt block, substantially as and for the purpose specified.

14. As an improvement in wagon-trucks, in

combination, a lower platform that is constructed from H-shaped metal bars arranged in line substantially with the draft and connected together at their ends, and an upper platform, which is composed of two H-shaped bars and a channel-bar, that are secured together by means of a circle-iron, substantially as and for the purpose shown.

In testimony that I claim the foregoing I have hereunto set my hand this 19th day of 25 February, 1890.

DANIEL S. TUTHILL.
